UNITED STATES PATENT OFFICE.

STANLEY A. HUFFMAN, OF NEWPORT, VIRGINIA.

CLUTCH-PEDAL LOCK.

Application filed June 23, 1922. Serial No. 570,298.

To all whom it may concern:

Be it known that I, STANLEY A. HUFFMAN, a citizen of the United States of America, residing at Newport, in the county of 5 Giles and State of Virginia, have invented new and useful Improvements in Clutch-Pedal Locks, of which the following is a specification.

The object of the invention is to provide 10 a simple and efficient means in the form of an attachment for motor-driven cars particularly of the Ford type to maintain the clutch pedal in an adjusted position, and more particularly to maintain the clutch 15 pedal of a machine of the indicated type in the low speed position while ascending long grades to relieve the operator of the necessity of holding the pedal; and furthermore to provide a pedal locking means which will 20 serve to lock a clutch or similar pedal in set positions and which may be readily disengaged to release the pedal when a further or different adjustment thereof is required in the operation of the car; and with these objects in view the invention consists in a construction and combination of parts of which a preferred embodiment is shown in the accompanying drawings, wherein:—

Figure 1 is a side view, and

30 Figure 2 is a rear elevation of a clutch pedal locking or holding means constructed in accordance with the invention and applied in the operative position to the clutch pedal of a car of the Ford type, the adjacent portions of the car being indicated in outline.

Figure 3 is a sectional view in the plane indicated by the line 3—3 of Figure 2.

Figure 4 is a detail view of the bracket 40 whereby the latch is pivotally mounted upon the clutch pedal.

Figure 5 is a detail view of the catch plate.

45 Figure 6 is a similar view of the latch operating spring.

The attachment consists essentially of a catch plate 10 adapted for arrangement on the car and engagement by bolts which are already in use on the standard or conventional types of Ford cars, and a latch 11

carried by the usual clutch pedal 12 and pivotally mounted to extend through a slot 13 in said catch plate, the latch bar being provided with ratchet teeth 14 for engagement with a detent or catch tooth 16 at one 55 end of the slot in the catch plate. A spring 17 serves to yieldingly hold the latch in engaging relation with the catch tooth or detent and a rubber or other cushion 18 at the opposite end of the slot serves to prevent the 60 rattling and jarring in the operation of the latch and also incident to the vibration of the car.

The bracket 19 whereby attachment is made to the clutch pedal and to which the 65 latch is pivoted as indicated at 20 is in the form of a clamp for engaging the shank of the clutch pedal to which it is secured by means of a bolt 21 or the equivalent thereof, and attached to or formed integral with the 70 latch is an operating arm 22 which curves forwardly and then rearwardly to terminate within convenient reach of the toe of a foot resting on the clutch pedal so that pressure applied to the extremity of said arm will 75 serve to disengage the latch from the catch tooth or detent to permit of readjustment of the clutch pedal whereas under normal conditions the latch serves by engagement with the detent of the catch plate to lock 80 the clutch pedal in either the neutral position as when starting the motor or in low gear as when ascending grades, without necessitating the constant pressure of the foot of the operator or driver.

85 In the construction illustrated the catch plate is provided with a forwardly directed securing arm 23 terminally perforated for engagement by the horn bolt 24 and with a lateral arm 25 terminally perforated for engagement by a bolt 26 of the side body brace 27, it being necessary merely to remove the taps of said bolts in order to position and secure the catch plate in its proper relation to the latch which is mounted as 90 above described upon the clutch pedal.

95 Having described the invention, what is claimed as new and useful is:—

A device for retaining the clutch pedal of an automobile in operative position com- 100

prising a catch plate having a slot, a latch bar pivoted at one end to the pedal and passing through the slot in the plate and having teeth which engage the edge of the slot, a spring interposed between the pedal and the bar to hold the teeth thereof in engagement with the edge of the slot and a

curved arm connected with the bar at a point between the ends thereof and having one end portion extending above the pivot and the upper end of the pedal.

In testimony whereof he affixes his signature.

STANLEY A. HUFFMAN.
